UNITED STATES PATENT OFFICE.

ORLANDO R. MARSH, OF CHICAGO, ILLINOIS.

ELECTRIC TAP.

1,290,623.

Specification of Letters Patent.

Patented Jan. 7, 1919.

Application filed November 23, 1915. Serial No. 62,985.

To all whom it may concern:

Be it known that I, ORLANDO R. MARSH, a citizen of the United States, and a resident of Chicago, Cook county, Illinois, have invented certain new and useful Improvements in Electric Taps, of which the following is a specification.

The general object of my invention is to provide an electric tap which shall be simple, durable, and inexpensive, and which shall be of such construction that it can be quickly and easily installed.

Another object of my invention is to provide an electric tap which will complement standard electrical devices, and which can be installed either when the standard electric device is initially installed or at a time subsequent to the initial installation; and which, when so initially or subsequently installed, shall become a substantial part of the device to which it is applied.

A further object of my invention is to provide an electric tap which can be installed in conjunction with present devices without in any way altering or cutting such devices, and which at the same time, when installed will appear as a part of the device itself and not as an obvious attachment therefor.

My invention consists generally in the novel form, arrangement and construction of the parts and in the method of application, whereby the above named objects, together with others which will appear herein-after are attained; and my invention will be more readily understood by reference to the accompanying drawings illustrating the preferred embodiment thereof.

In the said drawings:

Figure 1 is a vertical view of a standard form of wall switch, mounted in a wall, some of the parts being shown in elevation and others in section.

Fig. 2 is a front view of the switch with the canopy, or face plate, removed better to disclose the arrangement of the switch parts.

Fig. 3 is a perspective view of my novel switch completer and an electric plug for co-operation therewith.

Fig. 4 is a view similar to Fig. 1, but illustrating the application of the device shown in Fig. 3 to the switch.

Fig. 5 is a front view of the construction shown in Fig. 4 with the face plate, or

canopy, removed to disclose more clearly the arrangement and co-operation of the parts.

Fig. 6 is a sectional view through an ordinary electric wall outlet and bracket.

Fig. 7 is a face view illustrating my novel wall bracket completer and electric plug for co-operation therewith; and

Fig. 8 is a sectional view similar to Fig. 6 but illustrating the device of Fig. 7 placed in co-operating relation therewith.

In modern building construction it is the usual practice, where the building is wired for electricity, to provide wall switches for the more convenient operation of some of the lights, which are not within easy reach. With respect to other of the lights, however, such for example as a wall bracket, it is customary simply to provide a switch in the socket of the lamp. It often happens that it is desirable to operate some other electric device adjacent to a wall switch or adjacent to a wall bracket, and so, in some buildings, base board outlets are provided for this purpose. In a great many instances, however, no base board outlets are provided and even where they are provided they do not always provide the desired number of outlets in the desired locations. Furthermore, such base board outlets are expensive, that is to say, they cost as much to apply as any other outlet since they are a complete device in themselves and require the usual box, wiring, and insulation safeguards. It is my purpose to provide a method of and a means for providing desired additional outlets which shall be adapted for use and application either when the building is initially wired or at some subsequent time, but which, in either event, shall become in effect an integral part of the device to which it is attached and not simply a makeshift, protruding attachment which is both unsightly and unsubstantial.

To this end I have devised a method and means whereby devices, such for example as a wall switch or a wall bracket, can be complemented in such a way that they serve as a duplex or multiple outlet. To accomplish this purpose I provide a mat of insulating material substantially coextensive with the wall box to which it is to be applied, and in this mat I arrange suitable electric contacts formed and adapted to receive an electric plug at one end and to receive electric wires at the other. I provide a suitable opening in the mat to

permit projection therethrough of the electrical device which it surrounds, also preferably make the mat flat so that it can be placed against the wall and under the usual canopy or face plate where it is held in position by suitable means. In this way the face view of the mat is entirely hidden by the canopy so that close inspection is necessary to determine that it is not simply a 10 wall switch or a wall bracket of the usual construction.

Having thus stated generally the object, purposes, and construction of my device and its application to the uses intended, I shall 15 now describe it in detail in conjunction with several well known forms of wall boxes or outlets.

Referring first particularly to Figs. 1 to 5, inclusive, 2 represents the usual form of 20 metal box used for the housing of an electric device and which is permanently and rigidly secured in the wall 3 of the building. When the term wall is herein used, it shall be construed to mean either the wall, 25 floor, or ceiling, of the building. In this instance, the device which it houses is a wall switch 4. While my invention is not concerned with the exact construction of the switch 4, I shall, nevertheless, briefly describe the parts and its method of placement in the wall box 2. The box 4 is made of desired insulating material and contains metal members 5, 6, 7, and 8, threaded to receive binding screws 9, 10, 11, and 12. 30 13 and 14 are push buttons whereby the knife blade 15 may be caused to make or break the circuit between the opposite sides through the medium of the devices 16 and 17, and 18 and 19. Suitable electric wires 40 20, 21, 22, and 23 are carried to and secured upon the members 5, 6, 7, and 8, respectively. The switch box 4 is very rigidly and permanently secured to the wall box 2 by means of the plate 24 which extends between 45 ears 25 of the wall box, secured by the screws 26 and to the box 4 by means of screws 27. To hide the switch parts from view, it is customary to provide a face plate or canopy 28 which is secured to the plate 24 by means 50 of screws 29 coating with threaded openings 30 in the plate 24. In this manner the wall box 2 is rigidly secured in the wall of the building 3, and the switch 4 and canopy 28 are all securely and rigidly held in place. 55 It is very essential that the parts be rigidly held in place since considerable force is applied in operating the switch, and, in order that the device may be operated continuously without getting out of order, there 60 must be no relative movement of the parts which should be fixed. The switch just described simply serves the purpose of conveniently turning on or off a lamp or other electrical unit at some less convenient point. 65 It often happens that this switch is so lo-

cated that some other electrical device, such, for example, as a floor lamp, a piano lamp, or an electric fan, is desired in close proximity. To secure an outlet for this purpose, it has been hitherto necessary to consider this desire when installing the wiring and provide a base board outlet, or, as is generally the case, to carry a wire from a lamp fixture to the device. The first consideration is seldom given, and the second 70 expedient is unsightly. I obviate both of these objections by my novel method. For the purpose of providing an outlet at a point adjacent to a wall switch, I provide a mat of insulating material 31, slightly 75 larger than the wall box 2 and provided with an opening 32 of sufficient size to accommodate the switch 4. The mat 31 is provided with sockets 33 for the reception of the pins 34 of the plug 35 and with binding posts 36 and 37. I am not concerned with the actual form of plug and contacts and have therefore simply illustrated the pin and recess contact construction. I find it convenient to make a slight depression 37 80 in the mat adjacent the binding posts 36 and 37 so that they do not unduly project beyond the inner edge of the insulating mat. I also provide the mat with openings 85 38 above and below, through which a binding screw may be placed as will be shortly described. To apply this mat to the switch, it is but necessary to remove the canopy 28, loosen the screws 26 which hold the switch 90 4 in place, and then bodily pull the switch 100 outwardly. This can be readily done without interfering with the wiring, as there is always sufficient slack in the wires to permit such movement, and, in fact, the switch was originally so installed. This being done, 105 the mat 31 is slipped in place over the switch 4 and flat against the wall 3 of the building, and the screws 26 are replaced, the shanks thereof projecting through the holes 110 38 of the mat and the threaded ends engaging the lips 25 of the box 2. Wires 36^a and 36^b are then carried from the binding posts 9 and 11 of the switch to the binding posts 36 and 37 of the insulation mat as is best shown in Figs. 4 and 5. By attaching the 115 wires 36^a and 36^b to the proper binding posts of the switch, the outlet which I provide may be operated only when the switch is in operative position, or independent of the switch, as may be desired. When the 120 canopy 28 is replaced, as is indicated in Fig. 4, the switch has substantially the appearance which it had before, except that it is set out slightly from the wall, but by making the insulation mat of proper color, 125 it is hardly noticeable. I desire to call particular attention to the fact that no parts of the switch have been altered and that the outlet provided is rigidly and permanently secured to the wall box 2 so that there is 130

absolutely no danger of the mat 31 becoming loose in the course of constant and necessarily forcible insertion and retraction of the plug 35. This is of vital importance, especially in the large cities where devices of this kind must pass inspection by competent electrical experts. While I have described my device as being applied to a wall switch, subsequent to its initial installation in the building, it should be obvious that my outlet completer is equally applicable for installation and attachment to the box by the electrician when he is wiring the building. Furthermore, my device is a saving over present methods of providing additional outlets, in that the same wiring and same wall box serve for this additional outlet, thus saving the expense of running additional wires and providing an additional wall box.

I have thus far described my novel outlet completer in conjunction with a wall switch, but I wish it to be clearly understood that my invention is not by any means limited to use with such a device, and, for that purpose, I have illustrated in Figs. 6 to 8 inclusive, the application to the usual form of electric wall bracket. In providing a wall bracket, it is customary to mount a metal box 40 in the wall 41 of the building and to secure thereto the stem or pipe 42 of the electrical bracket by means of a suitable connector 43. Line wires 44 and 45 are carried to the box 40 through suitable conduits and just inside the box it is customary to remove the greater portion of the insulation and to provide sufficient free wire, as indicated at 46 and 47, to admit of convenient attachment of the fixture wires 48 and 49. For the purpose of providing an additional outlet at this place, I provide a mat of insulating material 50, which, in this instance, is circular or of such other form as may be necessary to conform to the canopy 51 of the fixture. The mat 50 is preferably made in two parts so that it can be conveniently separated for placement over the stem 42 and against the wall of the building. 52 indicates tongue and groove joints to permit convenient separating and replacing to form a rigid whole. In the body of the material suitable electric contacts 53 are provided for the reception of the pins 54 of the plug 55, and binding posts 56 are provided for the attachment of the line wires. To attach the line wires to the binding posts 56, the fixture does not need to be disturbed in any way, and it is but necessary to scrape off a small portion of the insulation from the free portions 46 and 47 of the line wires and place the same under respective binding posts, as indicated in Fig. 8. As before stated, there is always considerable slack or free wire in the fixture to permit such connection. In the edge of the insulating mat I provide an annular depression

57 to receive the rim 58 of the canopy 51. I prefer to remove the insulating material 70 which is usually placed around the base of the canopy, as it is possible to make a more sightly connection between the canopy and my outlet pad. The canopy is rigidly secured to the stem 42 by means of the binding screw 59, and when the insulating mat is placed in position, the screw 59 also serves to hold the mat against the wall. While this means alone might serve to hold the mat sufficiently in place, I prefer to provide additional means whereby the thrust and pull resulting from the forcible insertion and retraction of the electric plug may be taken care of. For this purpose I provide a standard 60 which is rigidly secured in the body of the insulating material, and which is provided with a loop 61 for straddling the stem 42 of the fixture. It is rigidly secured to the fixture by means of the screw 62. The thrust and pull resulting from the insertion and retraction of the plug is thus taken directly by the fixture stem or pipe 42, which, as before stated, is rigidly secured to the box 41 in the wall of the building. It is obvious, therefore, that my outlet, the insulating mat, is firmly and securely held in place.

The terms insulating mat, insulator mat, etc., as herein used, shall be construed to mean a mat in which the electrical contacts are suitably insulated, and not necessarily a mat all of the material of which is insulating material.

It is thought that the foregoing detailed description demonstrates the means whereby the object and purposes of my invention may be attained, but inasmuch as this disclosure will readily suggest to others modified devices whereby the substantial objects of my invention may be attained, I do not wish to be limited to the specific structure or structures herein shown and described, except as may be necessary by the scope of the hereunto appended claims.

I claim:

1. In a device of the class described, the combination of a wall box, a bracket projecting therefrom, a mat surrounding the wall box and provided with an aperture through which the bracket projects, electric contacts and binding posts in the mat, and a hanger member for suspending the mat from the bracket.

2. In a device of the class described, the combination of a wall box, a bracket projecting therefrom, a mat surrounding the same and containing electric contacts and binding posts provided with an aperture through which the bracket projects, the outer face of the mat being provided with a continuous depression, a hanger member for suspending the mat from the bracket, a canopy having its rim seated in the depression.

sion and provided with an opening through which the bracket arm projects and means to secure the canopy on the bracket.

3. An outlet adapter comprising in combination a wall box, an electric device in the wall box, a mat for surrounding the wall box, said mat being made up of sections having a central aperture to receive the electric device; electric contacts and binding posts in 10 one of the sections of the mat, means for sus-

pending the mat from the electric device and a canopy engaging the mat and secured in place on the electric device.

In testimony whereof, I have hereunto set my hand, this 16th day of November, 1915, 15 in the presence of two subscribing witnesses.

ORLANDO R. MARSH

Witnesses:

ARTHUR WM. NELSON,
JOHN R. LEFEVRE.
